UNITED STATES PATENT OFFICE.

WILLIAM A. SORG, OF MINNEAPOLIS, MINNESOTA, ASSIGNOR, BY MESNE ASSIGNMENTS,
TO FREDERICK B. BRADBURY, TRUSTEE, OF ST. PAUL, MINNESOTA.

COMBUSTION-ENGINE.

1,257,142.

Specification of Letters Patent. Patented Feb. 19, 1918.

Application filed March 2, 1914. Serial No. 821,911.

To all whom it may concern:

Be it known that I, WILLIAM A. SORG, a citizen of the United States, residing at Minneapolis, in the county of Hennepin and 5 State of Minnesota, have invented a new and useful Improvement in Combustion-Engines, of which the following is a specification.

Broadly this invention is a means to reduce friction by preventing the burning or carbonizing of lubricating oils and preventing hot gases from solidifying, or what is commonly termed cutting, the lubricating oil on the piston and piston rings in an internal combustion engine.

This engine is applicable to the various forms or types of combustion engines now in use. The following description sets forth exemplifications of the invention together 20 with additional advantages attained and novel features of construction and combinations of parts.

In the accompanying drawings forming part of this specification, Figure 1 is a longitudinal section of a fragment of a combustion engine showing my invention applied thereto; Fig. 2 is a plan of a type of engine such as disclosed in Fig. 1, also showing my invention; Fig. 3 is another longitudinal section of a fragment of a combustion engine of another construction to which my invention is applied; and Fig. 4 is an end view partly in section, of the construction disclosed in Fig. 1.

35 I will first describe the construction in detail disclosed in Figs. 1 and 2, after which there will follow a discussion of the operation and merits and advantages attained through the use of my invention. After said 40 discussion a description of the application of the invention to the type of engines disclosed in Fig. 3 will follow.

A indicates a reciprocable element or piston of usual construction carrying a pitman 45 2 which is connected to a crank shaft 3 in the usual manner, said crank shaft being journaled in bearings 4 upon the base 5 of the engine structure. The piston end of the pitman is journaled on the pin 6 carried by 50 the piston and the cylindrical outer wall of the piston is provided with the usual expansion rings 7 seated in annular grooves 8. The piston is fitted to reciprocate in a cylinder element B which carries a jacket 9 forming 55 a chamber 10 through which a cooling

medium such as water is adapted to circulate, suitable ports 11 and 12 being formed in the wall of the jacket for the ingress and egress of the cooling medium. A long tube C the bore of which is of materially less diameter than that of the cylinder, is provided with a flared end 13 terminating in an annular flange 14, which is secured by bolts 15 to an end of the cylinder as shown. The piston, cylinder and tube are co-axially arranged and the outer end of the tube is formed with suitable casings 16 and 17 in which an air ingress valve cage 18 and an exhaust valve 19 are respectively seated, said cage being secured in the casing 16, such as 60 by stud bolts 20 (see Fig. 4). A puppet valve 21 is seated in the inner end of the cage 18 and is adapted to admit air periodically into the outer end of the tube which passes into the cage through passages 22. 65 This valve has a stem passing through the outer wall of the cage and carrying on its outer end a nut 23 forming a head below which an expansion spring 24 is compressed against the cage and adapted to yieldingly 70 hold the valve 21 closed upon its seat. The puppet valve 19 is mounted in a similar manner to the valve 21 in the side wall of the outer end of the tube directly opposite the valve 21 excepting that it is seated directly 75 at 25 in the wall of the tube and that no cage such as 18 is employed. The diameter of the cage 18 is sufficient to permit of the insertion of the exhaust valve 19 on its seat 80 25 through the cage opening before the cage is placed. The outer end of the stem 16 on the exhaust valve is provided with an expansion spring 27 which is held compressed against the outer wall of the incasement 17 below the nut 28 on said stem whereby the 85 valve is adapted to close automatically. The incasement in which the exhaust valve is seated is formed with a chamber 29 having ports 30 and 31 to circulate a cooling medium such as water through the incasement 100 around the exhaust valve to prevent the latter from becoming overheated. The cooling chambers 10 and 29 are connected by a tube 32, so that the same cooling medium may be employed for cooling the cylinder and the 105 exhaust valve.

In the outer end of the tube C, a valve cage or manifold 33 is mounted, it being locked in place by means of a lock nut such as 34 threaded on its outer surface and 110

turned tightly against the end wall of the tube. In this cage or manifold a valve 35 is seated, which is adapted to admit fuel mixture through the passage in the cage 5 into the end of the tube at proper intervals during the operation of the engine. This valve has a stem 36 arranged longitudinally on the axis of the tube and slidably mounted in the outer portion of the cage 33. A nipple 37 is formed on the outer end of the cage through which the stem passes and a supporting arm 38 for a stop lever 39 to be hereinafter described is mounted upon said nipple, a lock nut 40 being threaded on the nipple and securing the support 38 tight against the end of the cage. The outer end of the stem 36 is provided with a flanged nut 41 and an expansion spring 42 is placed between the flange nut 41 and the lock nut 40 on the nipple 37, said spring being adapted to yieldingly hold the fuel valve 35 closed. The tension of the spring 42 is less than the tension of the spring 24, so that during the suction stroke of the piston A in the cylinder 25 the valve 35 remains closed while the valve 21 is forcibly opened, the valve 35 being adapted to open immediately upon the valve 21 closing during said stroke. In this manner air and fuel mixture are successively admitted into the tube and are caused to form in strata in the tube the fuel assuming the position near its outer end and the air assuring a position near the inner end of the tube before and after compression. The means for igniting the fuel is of ordinary construction and consists of the usual spark plug or other igniter such as 43 situated in the wall of the combustion chamber near the fuel valve, said spark plug being adapted 40 thereby to positively ignite the fuel stratum at one end and cause it to burn progressively toward the air stratum in the tube and thereby exert a continuous force against the piston during the working stroke.

45 The valves 21, 35 and 19 are operated successively and the amount of opening of the fuel valve is in direct ratio to the amount of load on the engine. The following mechanism is provided for accomplishing these 50 results which receives initial motion from any convenient source such as a counter shaft 44 which is suitably journaled in bearings 45 on the base 5 and operatively connected to the crank shaft by means of spiral 55 gears 46 and 47. The valve 21 is positively opened by a rocker arm 48 pivotally mounted between its ends on a support 49 upon the top of the cage 18, the outer end of said arm being connected to a trip arm 50 by a connecting rod 51, said trip arm being pivoted upon a portion of the base 5, and its free end provided with an antifriction roller 52, which bears upon a cam 53 carried by the countershaft 44. By this means one end of the rocker arm 48 is adapted to positively 65 open the valve 21 at fixed intervals and during the early portion of the suction stroke of the piston. The counter shaft 44 is made to revolve once during every cycle of operation of the engine and the valve 21 remains closed excepting for the period stated. The exhaust valve 35 is opened by the rocker arm 54 which is pivoted between its ends upon the base 5 with one end bearing against the nut 28 on the outer end of the exhaust valve 70 stem 26. The other end of said arm is provided with an antifriction roller 55 which rides upon a second cam 56 carried by the counter shaft 44. The cam 56 is so designed that every time the countershaft makes a revolution, the exhaust valve is opened and retained in open position for a sufficient period during the power and scavenging strokes of the piston to relieve the spent gases from the cylinder and combustion 75 chamber. The amount of opening of the fuel valve is also governed. The means for governing the amount of opening of the fuel valve consists of the stop 39 which is pivotally hung from the support 38 with its free end in the path of the inward motion of the flange on the nut 41, so as to limit the inward sliding motion of the valve. The stop arm 39 has its inward swinging movement 80 regulated by means of the screw 57 which is threaded horizontally and longitudinally of the engine through the support 38. One end of this screw impinges against a side of the stop arm 39 to define its position and the other end is turned by a series of interconnected arms 58, 59 and 60, said arm 60 being pivoted between its ends upon a support 61 carried by the base of the machine and one end being tiltably connected to the actuating element 62 of a speed governor 63. This speed governor may be of any suitable construction and has a revoluble driven element 64 operatively connected to the drive shaft 44 or any other suitable driving part of the engine. The revoluble driven element 64 carries the weighted governor arms 65 which are pivoted thereto with their extensions 66 pressing down upon the actuating element 62 against yielding spring pressure in the usual manner. After the engine operates any variation of load affects the speed of revolution of the counter shaft and any increase in speed of the countershaft affects the governor by causing its actuating element 62 to move and transmit the resultant force developed by any increase in speed to stop arm 39 which in turn is moved with its free end toward the flanged nut 41, thus limiting the opening of the valve 35. Decrease in speed of the countershaft caused by a heavy load on the engine acts in the opposite manner and permits the valve 35 to open wider admitting more fuel mixture into the end of 90 95 100 105 110 115 120 125

the tube. Located on the side of the cylinder and passing through its wall is a port 70, which is positioned so as to be uncovered by the piston near the outer end of its movement while reciprocating. This port passage 70 is in communication with a suitable source of water and air supply. The water supply being through a tube 71 tapped into the jacket chamber 29 and the air supply being through a passage 72 leading from the outer atmosphere. Interposed between the duct 70 and the tube 71 is a valve casing 73 in which is seated a check valve 74 which is adapted to simultaneously open a valve passage 75 to admit air into the cylinder and a duct passage 76 which communicates with the tube 71. The valve 74 is assisted in being closed by means of a spring 77 interposed between the outer end 78 of the stem of the valve and a guide support 79 in the valve casing through which the stem is adapted to slide, said spring also holding the valve against the pressure of water in the passage 76. Consequently, near the extreme outer end of the suction stroke of the piston, air and water are sucked up into the cylinder immediately adjacent the head end of the piston and during the power stroke of the piston, the valve 74 prevents the egress of the contents of the cylinder. The supply tube 71 is shown provided with a hand operable valve 80 which is adapted for use in closing the passage or regulating the amount of water which is adapted to be admitted through the port 70.

The advantages and features attained through the use of my invention in internal combustion engines are as follows:—

1.—More positive and reliable operation of the engine as well as the elimination of all starting troubles.

2.—The perfect combustion of all the fuel contained within the engine cylinder and combustion chamber.

3.—Complete stratification of the cylinder contents up to the time that ignition takes place.

4.—The complete mixing of the various strata of the cylinder contents after ignition.

5.—A means for burning heavy oils within the engine whereby the ordinary friction loss due to the incomplete lubrication, are avoided.

6.—A means for atomizing the fuel mixture uniformly at all loads and for preventing the loading up or accumulation of heavy oils on the lubricated portions of the cylinder.

7.—A means for retaining a more uniform compression in the engine at all loads.

8.—A means for preventing the hot gases from blowing into and around the piston rings and cutting the lubricating oil.

9th.—A means for keeping the stratum of steam in contact with the piston head and supplying steam packing for the piston and rings.

10th.—A means of preventing the mixing of the burnt gases which are retained within the clearance space after the scavenging stroke and mixing with the fuel mixture.

In operation, commencing at the beginning of the suction stroke, the mechanical air valve is opened by the cam 53 on the cam shaft 44 thereby admitting air freely into the cylinder. The air valve is held opened until the crank has turned about 90 degrees at which point it is closed. The effect of this opening is to supply a considerable quantity of cold air to the interior of the engine which naturally follows the piston during its forward movement with considerable velocity and consequently carries with it into the cylinder, the dead or burnt gas left within the tube from the previous power stroke. The valve spring 24 on the air valve being stronger than the one on the fuel valve, the effect of the closing of the air valve is to immediately open the fuel valve and the piston being at that point of its stroke when the velocity thereof is the highest a considerable vacuum is created, so that the fuel passing through the fuel valve 35 is atomized or broken up into very fine particles. The piston continues traveling until it uncovers the port 70, and this port being connected with the automatic valve 74 controlling the ingress of air and water, there follows an immediate inrush of air and a quantity of water in the form of a fog or spray. The particles of water coming in contact with the hot piston head and cylinder wall are immediately converted into steam. As a result counting from the piston head there occurs first a stratum of aqueous vapor, then a stratum of air and dead gas in the cylinder and then a stratum of ignitable fuel mixture contained wholly within the tube. This method of taking in water within the cylinder avoids all possibility of water or the resulting steam coming in contact and mixing with the fuel mixture at either light or heavy loads.

As the piston returns during the compression stroke, the water vapor in contact with the piston head is forced between the piston and cylinder walls and forms a backing between these surface walls in and around all of the piston rings and especially the first piston ring, thereby avoiding the burning or cutting of the lubricating oil. Continuing as the piston returns during the compression stroke the relative locations of the strata of the contents of the cylinder and tube are retained at the end of the stroke, the fuel mixture remaining adjacent the inner end of the tube. The spark plug

115

120

125

is located at such a point near the inner end of the tube as to cause a very small charge of fuel mixture to come into contact with it to be ignited. At a point ten or fifteen degrees before the end of the compression stroke, the fuel mixture is ignited by the igniter 43 and because the combustion of the rich mixture is relatively slow there occurs at dead center slightly increased compression of the contents of the tube by combustion and consequent expansion of a small portion of the gases. During the following power stroke the burning of the fuel mixture occurs, there being a large body of fire or flame which comes in contact with the enlarged diameter of the tube and which travels toward the piston head rigidly. As the flame advances toward the piston head the mixture being leaner (containing less and less fuel) and owing to the high temperature which is generated combustion continues and because of the excess of air, said combustion is substantially complete. This flame travel being within the cylinder and being influenced by the receding piston and owing to the shape of the tube in the cylinder the result is a mixing or swirling together of the entire cylinder contents. After the piston has reached about one-half its stroke, resulting in perfect combustion there follows a rapid drop in the temperature as the piston continues to move on the power stroke, thereby avoiding all after burning. When the piston reaches a point about 45 degrees before the end of the power stroke the exhaust valve is opened and the cylinder contents pass out through the combustion chamber into the atmosphere. The valve 74 automatically prevents the escape of gases during the power stroke. It will be noted that the fuel is admitted directly into the tube, it not being necessary to employ a carburetor or mixer to carburet the fuel before admission.

On the scavenging stroke the action of the piston is the same as in the conventional engine with the exception that the shape of the combustion chamber is such as to avoid any currents and to cause more of the burnt gases to pass out of the exhaust valve than is ordinarily the case.

In the construction illustrated in Fig. 3, this invention is shown applied to an engine of the general character described above in which an outside cylindrical piston 81 is slidably mounted upon a cylindrical bearing element 82, the latter carrying the tube 83 and otherwise corresponding in general construction to the structure set forth in the above description. The details of construction of this engine will be found in my companion applications for improvements in combustion engines filed on the 2nd day of March, 1914, bearing Serial Numbers 821,908, 821,909, and 821,910. The mode of

supplying air and water to the engine at the outer end of the suction stroke is by means of a sectional tube 84, one section being tapped into the water jacket surrounding the exhaust valve and the other section being secured to the valve casing 73 containing the valve 74 of similar construction to that disclosed in Fig. 1, said sections being telescopically jointed to compensate the free working of the piston on the cylinder. The joint between the telescopically connected sections is provided with a collar 85 threaded on one of the sections and containing packing 86 to produce a tight sliding connection.

Water and air may be supplied under pressure to the engine as above described by any suitable means such as a pump or compressor of any kind.

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention what I claim as new and desire to protect by Letters Patent is:—

1. A combustion engine, comprising, in combination, a piston, a cylinder in which said piston is reciprocable having a long tube detachably mounted on one of its ends forming a combustion chamber adapted to heat fuel therein and having a bore of materially less diameter than the inner diameter of said cylinder, the free end of said tube being formed with a valved inlet for fuel, a valved inlet for air and a valved outlet for the exhaust of spent gases, said cylinder being formed with a port in its side adapted to be uncovered by the piston near the end of the suction stroke, said port being valved to prevent the escape of the compressed cylinder contents during the working stroke and adapted to admit a medium into the cylinder at the end of the suction stroke in contact with the lubricating medium between the working surfaces of the piston and cylinder to protect said lubricating medium from the influence of the combustion of the fuel in the engine.

2. A combustion engine, comprising, in combination, a piston, a cylinder in which said piston is reciprocable having a long tubular extension, the bore of which is of less diameter than the inner diameter of the cylinder, the free end of said tube being formed with a valved inlet for fuel, a valved inlet for air and a valved outlet for the exhaust of spent gases adapted to successively admit first a portion of air and then a por-

- tion of fuel into said tube, so that they may form a layer of air and a layer of fuel when compressed during the compression stroke of the piston, means for positively igniting 5 the layer of fuel near one end of said tube and means for admitting air and water into said cylinder consisting of a port in the cylinder wall adapted to be uncovered by the piston near the end of the suction stroke and 10 a check valve adapted to close said port through the force exerted by the burning fuel in the engine during the working stroke, said air and water being adapted to form a film of medium in the cylinder in contact 15 with the lubrication upon the cylinder wall whereby the lubricating medium is protected from the influence of the burning fuel of the engine.
3. A combustion engine, comprising, in 20 combination, a piston and cylinder in reciprocable connection, one of said members forming a long tubular combustion chamber valved to admit air and fuel in separate strata therein and to exhaust spent gases, 25 ignition means placed near one end of said tube to ignite fuel, said cylinder being formed with a port in its wall adapted to be uncovered by the piston near the end of the suction stroke and means for admitting a 30 medium through said port into said cylinder for protecting the lubricating oil used between the working surfaces of the piston and cylinder from the influence of the burning fuel and gases and the products of combustion in the engine.
4. A combustion engine, comprising, in combination, a piston, a stationary element comprising a long tube forming a combustion chamber and a bearing element in the form of a cylinder on an end of said tube in 40 which said piston is slidably mounted, means for lubricating the adjacent surfaces between said cylinder and piston, means for admitting air into the outer end of said tube to prevent free ignition of the fuel by chilling the surface of the tube and carrying forward any incandescent particles of the products of combustion, means for admitting a charge of fuel into the outer end of said tube following the admission of said air, means 45 for exhausting spent gases from the tube, means for igniting the fuel charge in the tube whereby a prolonged force is exerted against the piston during the working stroke, said cylinder being formed with a 50 port in its side adapted to be uncovered by the piston near the end of the suction stroke, and means for admitting a medium through said port into said cylinder to protect the lubricating medium on the adjacent surfaces 55 of said cylinder and piston against the deteriorating influence of the combustion of fuel in the engine.

In testimony whereof, I have signed my name to this specification, in the presence of 60 two subscribing witnesses.

WILLIAM A. SORG.
